ELEVATING-TRUCK.

1,390,992.

Specification of Letters Patent. Patented Sept. 20, 1921.

Application filed January 11, 1918. Serial No. 211,334.

To all whom it may concern:

Be it known that I, DANIEL E. HENNESSY, a citizen of the United States, residing at Holyoke, county of Hampden, and State of Massachusetts, have invented certain new and useful Improvements in Elevating-Trucks, of which the following is a clear, full, and exact description.

This invention relates to elevating trucks 10 and particularly to elevating trucks of the type in which the elevation of the load is effected through mechanism operated from the steering and draft handle of the truck.

A general object of the invention is so 15 to incorporate a jack, and particularly a mechanically operated step-by-step jack, in a truck of the aforementioned type, that the load lifting capacity of the truck may be many times increased without materially 20 increasing the bulk of the truck, complicating its mechanism or interfering with its convenient handling in the restricted spaces in which such trucks must frequently be used.

More particularly the invention aims so to 25 incorporate multiplying levers in a truck, which has a load support arranged to be elevated by a combined lengthwise and upward movement of the support and a mechanically operated step-by-step jack extending lengthwise of the truck and arranged to be operated by the steering handle of the truck, that said levers will transmit to the jack from the handle, for each load 30 lifting step, a much increased load lifting power.

An important feature of the invention, which contributes particularly to the compactness of the truck construction, is the 40 provision, in combination with a jack extending lengthwise of the truck, of one or more multiplying levers arranged upright at the forward end of the truck, whereby the power applied by the operator to 45 the handle of the truck may be multiplied at the jack without materially increasing any dimension of the truck.

Another feature of the invention is the provision for automatic connection of the 50 steering handle to the elevating mechanism when the steering handle is moved into position conveniently to operate the elevating mechanism. Still other features and ob-

jects of the invention will appear from the following description and claims when considered in connection with the accompanying drawings, which illustrate the invention embodied in a truck of the type shown in my Patent No. 1,327,470, dated January 6, 1920.

In the drawings—

Fig. 1 is a plan view of a truck embodying the present invention, parts of the truck being omitted in order to show other parts upon a larger scale;

Fig. 2 is a side elevation with parts in 65 section, of the portion of the truck shown in Fig. 1;

Fig. 3 is a longitudinal section of the truck, showing details of the step-by-step jack mechanism and showing the arrangement of multiplying levers and the connection of these levers to the steering handle;

Fig. 4 is a rear elevation of the jack releasing means;

Fig. 5 is a bottom plan view of the mechanism shown in Fig. 4;

Fig. 6 is a rear elevation of the jack locking nut;

Fig. 7 is a rear elevation of the jack operating nut;

Fig. 8 is a modification showing parts of the invention embodied in a truck of the hydraulic jack type, the truck being shown in longitudinal section;

Fig. 9 is a longitudinal section to one side 85 of the section shown in Fig. 8 and illustrating more fully other parts of the truck which do not appear in the showing in Fig. 8, the full lines indicating the position of the parts when the platform is lowered, and the dotted 90 lines indicating the elevated position of the platform;

Fig. 10 is a plan view of the modified truck shown in Fig. 8;

Fig. 11 is an enlarged detail section on 95 the line 10—10 of Fig. 10; and

Fig. 12 is an enlarged transverse section on the line 4—4 of Fig. 10.

The illustrated truck is of the type having a single front steering wheel or a pair of 100 steering wheels carried by a member arranged to swivel at the front end of the truck, this member being connected to the steering handle, and the rear end of the truck being carried upon supporting wheels 105 at the end of an axle extending across the

truck, the truck being therefore a three wheeled truck with a single steering wheel and a pair of supporting wheels.

In the illustrated preferred embodiment 5 of the invention, the truck comprises a frame 2 having an upwardly and forwardly arched portion 4. At the forward end of the arched portion 4 of the frame is a vertical bearing in which the swivel pin 115 of a steering 10 fork 113 is arranged to turn, this steering fork carrying a steering wheel 112 upon a axle pin 114. At the rear of the frame, supporting wheels 111 are carried at the respective ends of an axle 109, extending 15 across the frame 2.

The elevating platform 6 is arranged for a compound movement of elevation upon the frame, comprising a shifting movement and a lifting movement, the platform being 20 maintained in parallelism to itself throughout this movement. This compound movement may be obtained in any suitable way, as, for example, by inclined members 123 and 124, such as shown in my patent here- 25 inabove referred to.

The jack by which the shifting and lifting movements of the platform 6 are effected is pivotally mounted upon the truck frame 2 so that it may swing about its pivots 8 as 30 the platform is raised, and this jack comprises a jack post 10 having rigidly attached to its outer end a head 12 pivoted between ears 14 on a bracket 16 attached to the underside of the platform 6. The jack 35 post 10 is provided with steep threads or grooves 18, the illustrated jack post having three of these threads. Mounted upon the jack post are two nuts 20 and 22, the nut 20 being threaded to coöperate with all three 40 of the threads 18 upon the jack post, and the nut 22 having two threads which co- 45 operate with two of the three threads 18 of the jack post. The purpose of this difference in the threading of the two nuts will appear hereinafter.

It will be noted that the threading of the jack post 10 is so steep that a movement of the jack post through the nuts 20 and 22, or a movement of the nuts 20 and 22 length- 50 wise of the jack post will cause the nuts to be turned upon the jack post. In order that advantage may be taken of this to effect a longitudinal movement of the jack post, provision is made for relative movements of approach and separation of the nuts and for alternately holding the nuts against turning. In the illustrated construction the nut 20 is mounted in a bearing member 24, which is carried upon the pivots 8 and is thus free to 55 turn about said pivots during the operation of the jack but is held against movement lengthwise of the frame 2. The nut 20 is provided with a conical clutching surface 26, which coöperates with the correspond- 60 65 ingly shaped inner face 28 in the rear end

of the bearing member 24. A cylindrical neck portion 30 of the nut 20 is received in a corresponding cylindrical bore 31 in the bearing member 24, said neck portion being threaded at its forward end to receive a nut 70 or collar 32 by which said nut 20 is confined in the bearing member, the collar 32 being so located upon the nut 20 that provision is made for movement of the nut 20 in the bore 31 whereby the clutching surface 26 upon the nut 20 may be moved into and out of engagement with the coöperating surface 28 upon the bearing member 24. This movement of the nut 20 through the bore of the bearing 75 80 85 90 95 100 105 110 115 120 125 130 member 24 is sufficiently free so that it will be effected by the movement of the jack post. The nut 22, like the nut 20, has a conical clutching surface 34 which coöperates with the correspondingly shaped inner surface 36 in a bearing member 38 for said nut 22. The nut 22, like the nut 20, also has a cylindrical neck portion 40 received in a cylindrical bore 41 in the bearing member 38 and threaded at its forward end to receive a collar 42 which confines said nut in its bearing. The bearing member 38 is provided with trunnions 44 which receive links 46 pivotally connected at 48 to a lever 50, of the second class, fulcrumed at 52 upon a bracket 54 at the forward end of the truck frame 2. Oscillation of said lever 50 about its fulcrum 52 effects, through the links 46, a reciprocation of the bearing member 38 upon the jack post 10. The nut 22, like the nut 20, is confined in its bearing member with provision for limited movement lengthwise of said member, whereby the surface 34 upon the said nut is moved into and out of clutching relation to the surface 36 on said member.

From the foregoing description it will be seen that when the bearing member 38 is moved toward the rear of the truck, that is, toward the right in each of the figures in which it is shown, it will be brought into clutching relation to the nut 22 and will not only carry the nut with it but will also prevent it from turning upon the jack post 10, thereby causing the jack post also to be moved with said bearing member. Such movement of the jack post moves the nut 20 out of clutching relation to its bearing member 24, whereby the nut 20 is free to turn upon the jack post as the jack post is moved through it. When the bearing member 38 is again moved toward the front of the truck, that is, toward the left in each of the figures in which it is shown, it moves out of clutching relation to the nut 22, thus permitting this nut to turn freely upon the jack post. At the same time the tendency of the jack post to move back to its original position causes the nut 20 to be moved into clutching relation to the bearing member 24, whereby this nut is prevented from turning and the

jack post is thus held substantially in the position to which it has been moved by the movement of the bearing member 38 toward the rear of the truck. The jack post being 5 held by the nut 20, the nut 22 is moved to a new position upon the jack post, and when the bearing member 38 is again moved toward the rear of the truck, the jack post is advanced still farther in its platform-lifting 10 direction.

A lever 56, fulcrumed at 58 upon the arched portion 4 of the truck frame, has a pin 60 received in a slot 62 in the upper end of the lever 50 and is provided with a stop 15 64 arranged to engage a stop 66 upon the truck frame to limit the rearward movement of said lever. The lever 56 may be connected in any suitable manner to the handle by which the truck is drawn and steered, where- 20 by it may be operated by a forward and backward movement of said handle to effect the oscillation of the lever 50, the connection to the draft handle of the truck being described more fully hereinafter.

25 It will be apparent that in order to release the jack to permit the load platform to be lowered, it is necessary that both the nut 20 and the nut 22 be permitted to turn freely upon the jack post 10. Means now 30 to be described has been provided for effecting the release of the jack, such means being preferably arranged to be operated by the foot of the operator. The means operating to hold the nut 20 in released position 35 will first be described:

The bearing member 24 for the nut 20 has a cylindrical extension 68 on the forward side of its pivotal axis, which is threaded to receive a cap 70, having a central bore 40 through which the jack post 10 moves, and having a stud 72 projecting from its front face below said jack post. The stud 72 serves as a crank pin by which the cap 70 may be screwed back and forth upon the cylindrical part 68 of the bearing member. 45 Between the inner face of the cap 70 and the forward end of the nut 20 is a washer 74. When the parts are in the position shown in Fig. 3, it will be seen that the washer 74 50 fills the space between the end of the nut 20 and the inner face of the cap 70, the nut 20 being in its released condition, thus preventing the nut from moving into clutching relation to its bearing member. This is the 55 released position of these parts and is not the normal position. In the normal position of these parts there is sufficient space between the inner face of the cap 70 and the seat for the collar 32, so that the nut 20 may move 60 freely into and out of clutching relation to the bearing member 24.

The means for moving the cap 70 into the position shown in Fig. 3 comprises a bell-crank lever 76 having on one arm an upwardly extending forked portion 78 which

embraces the stud 72, the other arm 80 of the bell-crank lever being bent upwardly out of the plane of the first mentioned arm, and having a universal joint connection 82 with a link or rod 84 connected at its other 70 end to the lower arm of a treadle lever 86, fulcrumed at 88 upon the truck frame. A spring 90 confined between the collar 92 on the rod 84, and an upstanding portion 94 of the truck frame, tends to hold the treadle 75 lever 86 in its elevated position and to hold the bell-crank 76 in such position that the cap 70 is maintained in the jack-operating position. In order that the nut 22 may also be held in such relation to its bearing member 38 that it will turn freely on the jack post as said post moves toward the platform-lowering position, an abutment 98 is provided against which the forward end of this nut strikes when the carrier 38 is moved 80 to its extreme forward position, thus effecting a relative movement of the carrier and nut into unclutching relation.

In order that the operator may retard the lowering of the platform, braking means 90 have been embodied in the jack-releasing means, the illustrated braking means comprising a conical friction surface 96 upon the collar 32, which co-operates with a correspondingly shaped friction surface upon 95 the inside of the bearing member 24. These two surfaces are preferably so shaped that they do not constitute a locking couple. It will be seen that as the operator presses his foot upon the treadle portion 87 of the treadle lever 86, he effects the turning of the cap 70 to release the locking couple 20, 24, and further depression moves the friction surface 96 into contact with the friction surface on the member 24, thereby retarding 100 the turning of the nut 20. The degree of the retarding action depends obviously upon the pressure exerted upon the treadle 87.

In order to limit the lifting movement of the jack, a plug or stop 97 is located in that 110 one of the threads 18 of the jack-post 10 which has no corresponding thread in the nut 22. The stop 97 will thus pass through the nut 22 and into engagement with the front end of the thread in the nut 20 which 115 travels in said groove or thread in which the stop is located. It will thus be seen that the jack can be extended by the operation of the nut 22 substantially to the end of the jack-post 10, and that the stop 97 will prevent 120 over-extension or movement of the jack-post 10 out of operative relation to the nuts.

As hereinabove suggested, an important feature of the invention is the arrangement, 125 in combination with a mechanically operated step-by-step jack, of a series of multiplying levers at the forward end of the truck so arranged that the lifting power transmitted from the truck handle to the 130

jack for each lifting step of the jack will be many times multiplied, this arrangement being such that the bulk of the truck is not increased nor the convenience with which 5 it may be manipulated in any way diminished. It will be noted that the lever 50, through which the lever 56 transmits its movement to the jack-extending clutch, has its respective lever arms so proportioned 10 that it constitutes a power multiplying lever in the chain of connections between the truck steering handle 118 and the jack, and that the lever 56 itself also has its arms so proportioned that it constitutes a power 15 multiplying lever in this chain of connections. At the upper end of the lever 56 is a link 134, through which connection is made to the steering handle 118, this link having at its forward end an enlarged portion 20 135 provided with a recess shaped to hook over a pin 136 extending between the fork members 119 of the steering handle 118. This enlargement 135 is so located upon the link 134 that when the link 134 25 is not connected to the steering handle 118, the enlargement or head 135 rests upon the upper end of the swivel bearing 116. At its forward end the head 135 is so beveled, as shown, that when the handle 118 is swung 30 into position to operate the jack, the pin 136 will engage the beveled face of the head 135 and cause the link 134 to ride up on the pin 136 until the recess in the head 135 comes into position over the pin 136, when 35 the link will drop into connected relation to the handle 118.

It will be noted that the link 134 connects the lever 56 to the handle 118 at such a point, with respect to the fulcrum of the 40 handle upon the axle pin 114, that with the usual length of steering handle, the steering handle itself multiplies the power exerted upon the handle by the operator, the whole chain of multiplying levers thus 45 transmitting to the mechanically operated step-by-step jack many times the lifting power exerted upon the handle by the operator, whereby the truck may be utilized to handle heavy loads.

50 In the modified form of the invention illustrated in Figs. 8 to 12 inclusive, a hydraulic jack of the type disclosed in my patent is shown, in combination with multiplying levers by which the power exerted 55 upon the handle is multiplied many times through the means by which it is transmitted to the jack. In this construction, however, it is not necessary to utilize so many multiplying levers to obtain the same 60 multiplication of power, since a multiplication of power is obtained in the jack itself, such multiplication by the well-known laws of hydraulics being in proportion to the relative areas of the pump piston and the 65 jack piston or plunger.

In the modified form of the invention, the base 110 of the truck is provided with rear wheels 111 and a front steering wheel 112, arranged substantially in the same manner as corresponding parts of the preferred form 70 of the invention, the steering wheel being carried by a steering fork 113 swiveled in a bearing 116, in a bracket 117 at the forward end of the base 110. The steering handle 118 is provided with bifurcation 119 fulcrumed upon the ends of the axle pin 114. The platform 120 of the truck may be of any suitable construction, and its side bars 121 and the side bars 122 of the base may be formed of angle metal, as shown in Fig. 12. 80

The platform normally rests upon the base and may be raised or lowered through the intervention of suitable mechanism, the mechanism for this purpose, herein illustrated, comprising inclined members 123 85 upon the base, presenting their inclined surfaces upwardly, and inclined members 124 upon the platform 120, presenting their inclined surfaces downwardly, the two inclined surfaces engaging for relative sliding 90 movement. The particular means for effecting the elevation of the platform constitutes no part of the present invention, and consequently may be replaced by other well known means for effecting a combined longitudinal 95 and vertical relative movement of the platform and base. The jack 126 and the associated pump 125 are preferably rigidly connected, the pump being provided with lateral bearing sockets 128 which receive suitable 100 pivot pins 129 rigidly mounted on the front portion of the base, as shown in Fig. 8. The piston rod 130, connected to a suitable piston within the pump 125 is connected by a link 131 to a lever 132 which is fulcrumed 105 upon the extension 117 of the base, the upper arm of this lever being longer than the lower arm and being pivotally connected at its end to the link 134, which is provided with a recessed head 135 adapted to be engaged with the pin 136 on the truck handle 118 in the manner hereinabove described in connection with the preferred form of the invention. When the handle is free from said link, the truck may be steered thereby, but when it is 110 engaged therewith, the piston 130 of the pump may be reciprocated by the oscillation of said handle, which serves as a hand-lever. 115

The ram 140 of the hydraulic jack is pivotally connected at 145 with the rear end of the platform 120, and the jack is so constructed with suitable valves, more fully described in my co-pending application Serial No. 194,591 hereinabove identified, that a step-by-step extension of the jack may be 120 effected and a corresponding step-by-step elevation of the platform. The hydraulic jack, like the mechanically operated jack hereinabove described, is laterally rigid and rectilinearly extensible and swings bodily 125 130

between its respective pivotal connections to the base and to the platform, as the platform is elevated upon the base.

The modified form of the invention, like 5 the preferred form, preferably includes manually controlled means for releasing the jack to permit the platform to move to its depressed position, the illustrated means including a valve, more fully shown and described 10 in the co-pending application Serial No. 194,591 hereinabove identified, this valve being controlled by a plunger 162 projecting to the outside of the jack casing and arranged in the path of an arm 167 on a 15 rock shaft 165 journaled in suitable bearings 166 on the truck base. An arm 171 on the rock shaft 165 is connected by a link 172 with a pedal 173 pivoted upon the base at 174. A spring 175 tends normally to keep 20 the pedal 173 in raised position and thereby to hold the arm 167 out of engagement with the plunger 162.

In order to prevent over-extension of the jack and elevation of the platform beyond a 25 predetermined limit, a link 169 is connected to another arm 168 on the rock shaft 165, and has a lost motion connection with the underside of the platform, comprising a nut 170 adjustably threaded upon the rod, this 30 nut being adapted to engage the end of the guide 180 when the platform reaches its uppermost position, whereby further movement of the platform will cause the rock shaft 165 to be rocked, thus bringing the arm 35 167 into engagement with the plunger 162 to prevent further extension of the jack.

What I claim as new is:—

1. In an elevating truck, the combination with a base having supporting and steering 40 wheels and an elevating support movable up and down upon said base, of means for effecting the up and down movement, comprising a step-by-step jack arranged and operating lengthwise of said base and a series of 45 multiplying levers having their long arms projecting upward and swinging in front of said elevating support at the forward end of said truck and having their fulcra vertically spaced, said series of levers having a positive 50 connection with said jack through which the oscillations of said levers are transmitted to said jack to effect the step-by-step movement thereof.

2. In an elevating truck, the combination 55 with a base, supporting wheels and a steering swivel, and an elevating support movable up and down upon said base, of means for effecting the up and down movement, comprising a mechanically operated step-by- 60 step jack arranged and operating lengthwise of said base beneath said support, a steering and draft handle mounted upon said swivel and means for operating said jack from said steering and draft handle, comprising a series 65 of multiplying levers arranged with

their fulcra in substantially vertical alignment between said elevating support and said steering swivel.

3. In an elevating truck, the combination with the truck base, supporting and steering 70 wheels for said base and an elevating support movable up and down upon said base, of means for effecting the up and down movement of said support, comprising a step-by-step jack extending lengthwise of said base, a 75 steering handle connected to the steering wheel to swing therewith and arranged to swing also in a vertical plane, and a multiplying lever for connecting said steering handle to said jack to effect the step-by-step 80 movement of said jack by the vertical swinging movement of said handle, said lever projecting upward in front of said elevating support and being connected to said handle above said steering wheel. 85

4. An elevating truck having, in combination, a truck base, a steering wheel having a swivel connection with the front end of said base, a steering handle pivoted upon the steering swivel, load lifting means, comprising a load support and a step-by-step 90 jack operating lengthwise of said base and beneath said load support, and operating connections between said steering handle and said jack, including a multiplying lever extending upwardly between said load support and said swivel and a link connecting the long arm of said lever with said handle above said swivel. 95

5. In an elevating truck, the combination with the wheeled truck base having a steering swivel at the front of said base, a steering handle connected to the steering swivel to swing therewith and vertically thereon, and an elevating support, of means for effecting the up and down movement of said elevating support upon said base, comprising a step-by-step jack operating lengthwise of said truck, a multiplying lever at the forward end of said truck having a depending 100 short arm connected to said jack and having a long arm projected at all times into the space between said elevating support and said steering swivel, and a power multiplying connection between said long arm and 105 said steering handle for operating said lever and said jack from said steering handle. 110

6. In an elevating truck, the combination with the wheeled truck base having a steering swivel at the front of said base, a steering handle connected to said swivel to swing therewith in steering and to swing vertically thereon, and an elevating support mounted upon said base for combined lengthwise and up and down movement thereon, of means 120 for effecting the movement of said support upon said base, comprising a mechanically-operated step-by-step jack extending lengthwise of said truck, a multiplying lever mounted upon said base between said jack 125 130

and said swivel and having a depending short arm connected to said jack, and a long arm located at all times in the space between said elevating support and said swivel and arranged to be connected to said steering handle to be operated by the vertical swinging movement thereof.

7. In an elevating truck, the combination with a wheeled base, load lifting means com-

prising a load support and a step-by-step 10 jack operating lengthwise of said base beneath said load support, and jack releasing means having a lost motion connection with said load support.

Signed at Holyoke, Massachusetts, this 15 15th day of December, 1917.

DANIEL E. HENNESSY.
